MACHINE FOR TESTING PERFORATIONS IN TEAR OPEN CARTONS

Martin J. Galbraith and Wendell T. Burbank, Kalamazoo, Mich., assignors, by mesne assignments, to KVP Sutherland Paper Company, a corporation of Delaware

Filed Feb. 24, 1959, Ser. No. 794,893

8 Claims. (Cl. 73—102)

This invention relates to improvements in a machine for testing perforations in tear open cartons. The principle objects of this invention are:

First, to provide a machine for applying tearing or opening pressure to perforated carton blanks and to provide a measurable indication of the pressure at which the blank tears or separates.

Second, to provide a machine for uniformly supporting and grabbing a test blank carton with tear open perforations therein and for advancing spring pressed pressure members against the carton blank until the blank tears or separates along the perforations.

Third, to provide a machine for testing tear open carton blanks in which a primary pressure member is advanced first against an initial tear point on the carton blank and secondly pressure bars are then advanced against adjacent portions of a tear line in the carton blank to record the pressures required to tear the various portions of the tear line in the blank.

Other objects and advantages of the invention will be apparent from a consideration of the following description and claims. The drawings, of which there are two sheets, illustrate a highly practical form of the testing machine and one type of carton blank on which the machine is adapted to operate.

Fig. 1 is a fragmentary front elevational view of the testing machine in retracted position with parts broken away.

Fig. 2 is a fragmentary plan view of a portion of a carton blank which the machine is adapted to test.

Fig. 3 is an end elevational view of the machine partially broken away in cross section.

Fig. 4 is a fragmentary horizontal cross sectional view taken along the plane of the line 4—4 in Fig. 3.

Fig. 5 is a fragmentary enlarged cross sectional view through the carton blank taken along the plane of the line 5—5 in Fig. 2.

Fig. 6 is a fragmentary cross sectional view similar to Fig. 5 but illustrating the blank in torn or opened condition.

The producers of various packaged commodities utilizing cardboard cartons and provided with perforated tear out panels for ease in opening the cartons have placed increased limitations of uniformity on the manufacturers of cartons and carton blanks and have become increasingly critical of the uniformity of opening pressure required in their cartons. It has therefore become a problem to the manufacturers of cartons and carton blanks to determine with considerable accuracy just how much pressure is required to sever the perforated tear line of any given carton blank. The present invention provides a machine for accurately determining and comparing the relative resistance to tearing of the perforated tear lines of different carton blanks. Since cardboard cartons are uniformly made up in flat cardboard blanks with scored fold lines and perforated tear lines where desired, the machine of the invention is designed to oper-

2

ate on the flat carton blanks rather than on erected box-like cartons.

Fig. 1 illustrates the machine of the invention as consisting of a base 1 of suitable rigidity having a pair of upright posts or columns 2 projecting thereabove and forming a slideway above the center of the base. The upper ends of the columns are connected by a cross bar 3 and the columns form a vertical slide support for a carriage 4. Projecting forwardly and relatively downwardly from the column engaging portion of the carriage 4 is a vertical plate 5 having a forwardly projecting lower flange 6 and an upwardly spaced intermediate flange 7. A top flange 8 is spaced considerably above the intermediate flange 7 and provided with tapped apertures adjustably receiving the abutment screws 9 and 10. Two abutment screws 9 are spaced laterally at the sides of the top flange 8 and the center abutment screw 10 is offset slightly to the rear of the line between the screws 9.

The lower and intermediate flanges 6 and 7 have holes formed therein forming guideways for the side plunger rods 11 and a center plunger rod 12. The upper ends of the plunger rods have heads 13 engageable with the intermediate flange 7 and positioned opposite the abutment screws 9 and 10. Pressure springs 14 are compressed between the heads 13 and heads 15 on the abutment screws.

The lower end of the center plunger rod 12 carries a ball shaped head 16 and the lower ends of the side plunger rods 11 carry pressure bars 17 that are inclined upwardly at their sides as indicated in Fig. 1 and inclined or angled forwardly as indicated in plan view in Fig. 4. Guide rods 18 secured to the pressure bars and extended slightly upwardly through the lower flange 6 maintain the pressure rods 17 in their angled positions.

Supported on the base 1 in front of the columns 2 and underneath the carriage 4 is a support plate 19. The plate 19 is secured in place by screws 20, the heads of which project upwardly and form guides for a moveable pressure plate 21 positioned over the support plate. Springs located between the corners of the plates as at 22 in Fig. 3 bias the pressure plate upwardly from the support plate. The plates 19 and 21 define central angled openings or holes as at 23 in Fig. 4 that are substantially co-extensive and located underneath the pressure ball 16 and the pressure rods 17.

Mounted on each end of the base 1 are bearing brackets 24 supporting rock shafts 25 having operating handles 26 and hold down cams 27 eccentrically mounted thereon over the ends of the pressure plate 21. A carton blank to be tested can be slipped between the plates 19 and 21 and the cams 27 actuated to tightly and uniformly grab the tapped blank with the perforated tear portion of the blank exposed within the openings 23.

An electrical drive motor 28 mounted on the rear of the base is connected to a gear reduction or transmission 29 having a drive shaft 30 projecting thereabove. A coupling 31 connects the drive shaft to the lower end of a screw 32 which extends upwardly through the carriage 4 and has its upper end journaled in the cross bar 3 as at 33. Limit switches 34 and 35 adjustably mounted on one of the columns 2 have their actuating tappets 36 positioned to be engaged alternately by the control brackets or plates 37 secured to the back of the carriage. The limit switches are connected through cables 38 to the motor to reverse the motor and the screw when the carriage reaches the upper and lower limits of its travel as will be readily understood. A manual control switch 39 is provided on the base for turning the machine on and off.

Secured to the front edges of the upper flange 8 and intermediate flange 7 and in front of the springs 14 are indicia plates 40 having guide slots 41 in their lower

ends. Indicator blocks 42 are slidably positioned in the slots 41 and frictionally engaged with the edges of the slots to maintain adjusted positions on the indicator plates. The rear edges of the indicator blocks 40 project into the path of movement of the heads 13 on the plunger rods 11 and 12.

The angled opening 23 and the angled position of the pressure bars 17 of the machine as disclosed are particularly adapted to test the perforation of a particular type of carton blank 43 as shown in Figs. 2, 5 and 6. This carton blank has an end wall 44 with score lines 45 foldably connecting the end wall to side walls of a carton. An angled line of spaced short perforations 46 extends across the midportion of the end wall 44 and continues across the adjacent corners of the side walls of the carton. The perforations 46 may extend completely through the thickness of the blank 43 but due to the length and multiplicity of uncut spaces between the perforations, the tear line forms a definite resistance to tearing which can be varied by varying the length of the slits 46. Positioned in slightly offset parallel relation to the line of perforations 46 is an angled slit 47 which extends only to the side edges of the end wall 44 and which does not extend completely through the thickness of the blank as appears more clearly from Fig. 5. One or more short interruptions or unslit areas 48 may be provided in the elongated slit 47 to vary the resistance of the blank to tearing along the elongated slit 47. This type of carton perforation is designed to tear relatively easily by lateral pressure applied at the apex of the angled slit 47 by tearing away the inner surface of the blank between the lines of the slits 46 and 47 as indicated at 49 in Fig. 6. Once the blank has been ruptured the tearing or opening operation can be continued along the side walls of the carton by tearing outwardly and upwardly on the end wall of the carton.

A carton blank of the type described is easily inserted and clamped between the blanks 19 and 21 and the resistance to tearing of the several parts of the perforated blank are measured by actuating the motor 28 to progressively lower the carriage 4. The ball shaped head 16 first engages the center of the blank and the resistance to deflection of the blank causes the center plunger rod and its head 13 to rise against the resistance of the spring 14 raising the indicator block 42 until sufficient pressure is created to rupture the center of the carton blank. The position of the block 42 on the scale blank 40 permanently indicates the pressure at which initial rupture of the carton took place. Continued downward movement of the carriage 4 presses the lower inner ends of the inclined pressure bars 17 against the initially ruptured ends of the tear line and progressively tears the carton along the perforated tear line 46. The resistance to tearing is measured on the side indicia plates 40 as the plunger rods 11 are forced upwardly against their backing springs.

By use of this machine standard resistance to tearing can be established and the degree of slitting or perforating carton blanks can be adjusted by the carton manufacturer to maintain any desired opening pressure for blanks by a manufacturer.

What is claimed as new is:

1. A tester for carton perforations comprising a base having a flat support plate defining an angled central opening shaped to surround the perforation to be tested, a clamp plate yieldably supported in spaced relation above said support plate and having an opening substantially coextensive with the opening in said support plate, means including cam rollers mounted on said base at each end of said support plate and extending thereacross to move said clamp plate toward said support plate to clamp a carton blank between the plates, a pair of upright columns forming a guideway on said base perpendicular to said plates and offset therebehind, a carriage slidable on said guideway and having spaced parallel flanges overlying said plates and the openings therein,

70 a first plunger rod slidably guided in the center of said flanges and having a ball shaped head on its lower end opposite one part of said openings, side plunger rods slidable in said flanges parallel to said center rod and offset laterally therefrom along the angle of said openings, elongated pressure bars secured to the lower ends of said side plunger rods and movable thereby through said openings, guide rods secured to said pressure bars in spaced relation to said side plunger rods and slidably guided in the lower of said flanges, heads on the tops of said plunger rods engaging the top of the upper flange, spring abutments adjustably mounted on said carriage in spaced relation to the heads on the tops of said plunger rods, springs positioned between said abutments and said heads on the tops of said plunger rods, scale plates mounted on said carriage opposite each of said springs and defining indicator slots, indicator blocks slidably mounted and frictionally engaged in said slots with their rear ends projecting into the paths of movement of the heads on said plunger rods, scale indicia on said scale plates cooperative with said indicator blocks, means including a screw mounted parallel to said guideway and engaged with said carriage and a motor connected to rotate said screw to raise and lower said carriage, and limit switches mounted to be actuated by movement of said carriage and connected to control said motor.

2. A tester for carton perforations comprising a base having a flat support plate defining a central opening shaped to surround the perforation to be tested, a clamp plate yieldably supported in spaced relation above said support plate and having an opening substantially coextensive with the opening in said support plate, means on said base to move said clamp plate toward said support plate to clamp a carton blank between the plates, a guideway on said base perpendicular to said plates and offset therebehind, a carriage slidable on said guideway and having spaced parallel flanges overlying said plates and the openings therein, a first plunger rod slidably guided in the center of said flanges and having a head on its lower end opposite the center of said openings, side plunger rods slidable in said flanges parallel to said center rod and offset laterally therefrom along the angle of said openings, elongated pressure bars secured to the lower ends of said side plunger rods and movable thereby through said openings, heads on the tops of said plunger rods engaging the top of the upper flange, spring abutments adjustably mounted on said carriage in spaced relation to the heads on the tops of said plunger rods, springs positioned between said abutments and said heads on the tops of said plunger rods, scale plates mounted on said carriage opposite each of said springs and defining indicator slots, indicator blocks slidably mounted and frictionally engaged in said slots with their ends projecting into the paths of movement of the heads on said plunger rods, scale indicia on said scale plates cooperative with said indicator blocks, means including a screw mounted parallel to said guideway and engaged with said carriage and a motor connected to rotate said screw to raise and lower said carriage, and limit switches mounted to be actuated by movement of said carriage and connected to control said motor.

3. A tester for carton perforations comprising a base having a flat support plate defining a central opening shaped to surround the perforation to be tested, a clamp plate yieldably supported in spaced relation above said support plate and having an opening registering with the opening in said support plate, means on said base to clamp said plates together to clamp a carton blank between the plates, a guideway on said base perpendicular to said plates and offset therebehind, a carriage slidable on said guideway and having a flange overlying said plates and the openings therein, a first plunger rod slidably guided in the center of said flange and having a head on its lower end opposite the center of said openings, side plunger rods slidable in said flange parallel to said center rod and offset laterally therefrom, elongated pressure bars secured

to the lower ends of said side plunger rods and movable thereby through said openings, heads on the tops of said plunger rods engaging the top of the flange, spring abutments adjustably mounted on said carriage in spaced relation to the heads on the tops of said plunger rods, springs positioned between said abutments and said heads on the tops of said plunger rods, scale plates mounted on said carriage opposite each of said springs and defining indicator slots, indicator blocks slidably mounted and frictionally engaged in said slots with their ends projecting into the paths of movement of the heads on said plunger rods, scale indicia on said scale plates cooperative with said indicator blocks, and means including a screw mounted parallel to said slideway and engaged with said carriage and a motor connected to rotate said screw to raise and lower said carriage.

4. A tester for carton perforations comprising a base having a flat support plate defining a central opening shaped to surround the perforation to be tested, a clamp plate yieldably supported in spaced relation above said support plate and having an opening registering with the opening in said support plate, means on said base to clamp said plates together to clamp a carton blank between the plates, a guideway on said base perpendicular to said plates and offset therebehind, a carriage slidable on said guideway and having a flange overlying said plates and the openings therein, a first plunger rod slidably guided in the center of said flange and having a head on its lower end opposite the center of said openings, side plunger rods slidable in said flange parallel to said center rod, elongated pressure bars secured to the lower ends of said side plunger rods and movable thereby through said openings, heads on the tops of said plunger rods engaging the top of the flange, spring abutments adjustably mounted on said carriage in spaced relation to the heads on the tops of said plunger rods, springs positioned between said abutments and said heads on the tops of said plunger rods, scale plates mounted on said carriage opposite each of said springs and defining indicator slots, indicator blocks slidably mounted and frictionally engaged in said slots with their ends projecting into the paths of movement of the heads on said plunger rods, scale indicia on said scale plates cooperative with said indicator blocks, and means to raise and lower said carriage.

5. A tester for carton perforations comprising a base having a flat support plate defining an opening shaped to surround the perforation to be tested, a clamp plate yieldably supported in spaced relation to said support plate and having an opening registering with the opening in said support plate, means to clamp said support plates together to clamp a carton blank between the plates, a pair of upright columns forming a guideway on said base perpendicular to said plates and offset therebehind, a carriage slidable on said guideway and overlying said plates and the openings therein, a first plunger rod slidably guided in said carriage and having a ball shaped head on its lower end opposite one part of said openings, another plunger rod slidable in said carriage parallel to said first rod and offset therefrom along said openings, an elongated pressure bar secured to the lower end of said other plunger rod and movable thereby through said openings, a guide rod secured to said pressure bar in spaced relation to said other plunger rod and slidably guided in said carriage, means on said plunger rods engaging said carriage to limit movement of the rods toward said plates, spring abutments adjustably mounted on said carriage in spaced relation to the ends of each of said plunger rods, springs positioned between said abutments and the ends of said plunger rods, scale plates mounted on said carriage opposite each of said springs, indicator blocks slidably mounted and frictionally en-

gaged on said plates with their rear ends projecting into the paths of movement of said plunger rods, scale indicia on said scale plates cooperative with said indicator blocks, and means to raise and lower said carriage.

- 5 6. A machine for testing the rupturing strength of cartons comprising a base having a flat support plate defining an opening shaped to surround the area to be tested, a clamp plate yieldably supported in spaced relation to said support plate and having an opening registering with the opening in said support plate, means to clamp said support plates together to clamp a carton blank between the plates, a guideway on said base perpendicular to said plates and offset therebehind, a carriage slidable on said guideway and overlying said plates and the openings therein, a first plunger rod slidably guided in said carriage and having a head on its lower end opposite one part of said openings, another plunger rod slidable in said carriage parallel to said first rod and offset therefrom along said openings, an elongated pressure bar secured to the lower end of said other plunger rod and movable thereby through said openings, a guide rod secured to said pressure bar in spaced relation to said other plunger rod and slidably guided in said carriage, means on said plunger rods engaging said carriage to limit movement of the rods toward said plates, spring abutments adjustably mounted on said carriage in spaced relation to said plunger rods, springs positioned between said abutments and said plunger rods, indicator blocks slidably mounted and frictionally engaged on said carriage with their ends projecting into the paths of movement of said plunger rods, scale indicia on said carriage cooperative with said indicator blocks, and means to raise and lower said carriage.

- 20 7. A machine for testing the rupturing strength of cartons comprising clamp means for clamping a carton blank in spaced relation to the area to be tested, a support, a plurality of plunger rods slidably mounted on said support independently of said clamp means and in opposed relation to said clamp means and the test area of a carton blank held thereby, adjustable spring means biasing said plunger rods on said support toward said clamp means, means for moving said clamp means and said support toward each other, and means including slidably mounted frictionally located indicators on said support located in the paths of movement of said plunger rods for indicating the movement of said plunger rods on said support against the resistance of said spring means due to the resistance of a carton blank to movement of said plunger rods by said support.

- 25 8. A machine for testing the rupturing strength of cartons comprising clamp means for clamping a carton blank in spaced relation to the area to be tested, a support, a plurality of plunger rods slidably mounted on said support independently of said clamp means and in opposed relation to said clamp means and the test area of a carton blank held thereby, spring means biasing said plunger rods on said support toward said clamp means, means limiting movement of said rods on said support toward said clamp means, means for moving said clamp means and said support toward each other, and means for indicating the movement of said plunger rods on said support against the resistance of said spring means due to the resistance of a carton blank to movement of said plunger rods by said support.
